UNITED STATES PATENT OFFICE.

CHARLES BOWTELL SMITH, OF DUNEDIN, NEW ZEALAND.

GENEVA-GEAR NUMBERING AND RECORDING MACHINE.

No. 825,162.

Specification of Letters Patent.

Patented July 3, 1906.

Application filed February 20, 1905. Serial No. 246,630.

To all whom it may concern:

Be it known that I, CHARLES BOWTELL SMITH, printer, a subject of the King of Great Britain, residing at 49 Moray Place, in the 5 city of Dunedin, in the British Colony of New Zealand, have invented a new and useful Geneva-Gear Numbering and Recording Machine, of which the following is a clear, exact, and full description.

The object of this invention is to produce a machine for numbering or printing numbers in ink.

The special feature of this machine is that all wheels on which the numbers are engraved are connected by gearing at all times to the prime mover or star-wheel, and no gearing or number-wheels are dependent on springs. Each set of number-wheels can be quickly detached to alter for printing in various positions on sheets of paper or to be set to zero. Several number sets may be fixed for the various work in printing, and in addition to plain consecutive numbering, as "1, 2, 3," &c., other numbering progressions can be done, such as "1, 6, 11," &c., or quintuple, to be described. As the gearing is direct, in case of misprint or failure to lay a sheet the prime mover can be returned to cause all sets of number-wheels to number back to a desired number. The machine can also do duplicate, triplicate, or quadruplicate numbering, as will be described.

Referring to the accompanying drawings, Figure 1 is a front elevation of the machine, with the paper-holding table removed, and Fig. 2 is a side view of same, but with table in position. Fig. 3 is a diagram of the partly-hidden inking device indicated in Fig. 2. The remaining figures are to a larger scale. Fig. 4 is an elevation of certain change-gear for altering the numbering progressions from consecutive numbering when needed, and Fig. 5 is a sectional view taken upon the line 5-5 of Fig. 4 looking in the direction of the arrow of one-half of the change-gearing. Fig. 6 is an elevation of a numbering set, showing the gearing to all numbering-wheels; and Fig. 7 is half a cross-section of same. Fig. 8 is a slight modification of the arrangement of the numbering-wheels, allowing them to be fixed closer together, as often needed for rotary-machine numbering, being half a cross-section; and Fig. 9 is an elevation of same. Fig. 10 is an elevation of the number-wheels-securing device and Fig. 11 is an end view of same with part of the section of

the reel-rim, showing attachment to same. Fig. 12 is a similar view to Fig. 6, but slightly enlarged to show parts better and with the disks drawn slightly apart for showing the 60 separate groups of gearing that are secured together and where they can be separated. Fig. 13 is the elevation of a group on the driving-shaft, but with the units shown separately that are normally secured together. 65 Fig. 14 is a similar elevation of a group on the center shaft, but separated for same purpose. Fig. 15 is a printing group also with the pieces separated to show same clearly. In these three groups the connecting pin or 70 rivet holes are shown that bind them normally together. Fig. 16 is a detail of the wheel, cam-disk, and pin for moving said pin, as will be explained; and Fig. 17 is an elevation of the disk, showing places for pins. 75

A is the frame of the machine.

B is the lower or bed roller in one length or in reels having the driving-pulleys B³ on its end.

C is the main shaft, geared to B by spur-wheels B' C'. On shaft C are secured the reel-frames D D', shown without the change-wheels or numbering-wheels, respectively, in Figs. 1 and 2; but furnished with these in the details where they occur. 80

D D' are the reel-frames for holding the change-wheels, and five changes are shown.

E' is the prime mover, which may conveniently be a five-armed star-wheel to which any one pair of the change-wheels can be 90 geared, the other four pairs having at least one of its wheels loose or the whole would lock. Therefore when one or more sets of number-wheels are in position between the disks D' D' and the pair of change-wheels E, 95 being sixteen teeth on the star-spindle and thirty-two teeth on the shaft F, are fixed by the tightening of the set-screw shown which enters a countersunk depression in shaft or spindle (not shown) and the star-wheel E' 100 made to contact once at each revolution of C and D, and consequently of D', with a projecting pin U in the fixed disk T, the result is one-tenth of a revolution of each units-wheel geared to same and the numbering is 105 "1, 2, 3, 4," &c., in all such sets. If two or four sets of numbering-wheels are placed in position with the figures of same set alternately at "1" and "2" and the wheels E' 110 fixed, being twenty-five teeth on each, and the star-wheel E' made to contact once at each revolution of D with said pin U, the re-

sult is two-tenths of a revolution of each units-wheel geared, and the resulting numbering is "1, 3, 5, 7," &c., on alternate number-wheels and "2, 4, 6, 8," &c., on the others. 5 If either E^3 , E^5 , or E^7 were fixed and the star-wheel E^0 made to contact once at each revolution of D with said pin U, other numbering combinations would be effected, as E^3 gives a three-tenth, E^5 a four-tenth, and E^7 a five-tenth movement to the units-wheels, respectively, under the above conditions. With one, two, three, four, or five pins inserted in holes on the face of said disk T and the star-wheel E^0 made to contact with a pin after 10 each impression of numbers all the before-mentioned styles of numbering can be done—namely, the consecutive, duplicate, triplicate, quadruplicate, and quintuple; but the duplication or triplication of sheets cannot 15 thus be effected. For this purpose only one pin U is used in disk T, and it is made to recede at intervals by means shown and to be described.

For convenience the several groups of 20 wheels and numbering sets are usually placed on sleeves, as indicated in the drawings, merely to retain said groups together conveniently.

The shaft F is extended through all reel-frames on the shaft C. Two of these reel-frames are shown without gear in them in 25 Fig. 1. In these frames (see Figs. 6, 7, and 12) the spur-wheel F' is secured to shaft F. F' has twenty-five teeth and gears to a loose wheel G' of thirty teeth on shaft C, to which shaft all reel-frames D D' D' are secured. Secured to this thirty-teeth wheel G' so loose 30 on shaft C is a thirty-six-teeth wheel G, which gears to a thirty-teeth wheel H, which is secured to the first or units-wheel of the numbering set. Said wheel F' is also secured to a one-tooth Geneva wheel I, which gears to a twelve-notched and concaved Geneva wheel J, which 35 is secured to the adjacent thin thirty-six-teeth wheel G², which gears to a thin thirty-teeth wheel H³, which is fixed to the tens number-wheel H'. It will be seen that the 40 tens-wheel is correctly moved, as thirty-six teeth is to thirty teeth so is the twelve-notched Geneva wheel to the ten figures on the number-wheels. It is obvious that in 45 specifying the numbers of teeth other numbers in same proportions in any gear could be used. Attached to the said twelve-notched Geneva wheel J and the said adjacent thirty-six-teeth wheel G is a thirty-teeth wheel G'. These three are all secured together, the 50 thirty-teeth wheel G' gearing to a twenty-five-teeth wheel F' on shaft F, which in turn 55 is secured to the second one-tooth wheel (Geneva) I' and a washer of the thickness to clear the next thirty-six-teeth wheel G. This second one-tooth Geneva wheel I' gears to another twelve-notched Geneva wheel J, 60 which is a part of the next set comprising

itself, a thirty-six-teeth wheel G and a thirty-teeth wheel G' operating the hundreds-wheel of the numbering set and also working back in similar manner to work the thousands-wheel, and so on to the actual number of figure-wheels comprising a full set. This Geneva gear prevents any movement other than that imparted by the star-wheel till any set is ungreased, when all number-wheels are loose. Other sets can be placed round the wheels on 75 shaft C, as seen in dotted lines in Fig. 7 by H²H.

The machine as shown and described (omitting Figs. 8 and 9) is adapted for a general jobbing numbering-machine complete; but the shaft C alone, with its reels and gear, 80 may be geared to the printing-cylinder of any reciprocating printing-machine and be supplied with ink from the ink-rollers of said machine, so that numbering can be worked in conjunction with printing. The modification shown in Figs. 8 and 9 is an arrangement of sets of numbering-wheels placed close together or at regular intervals to permit of numbering a continuous strip either separately or in conjunction with rotary printing-machine. In this arrangement all outer sets are numbering sets. F is moved out to the center of the dovetailed groove, round which the other numbering sets are adjusted and fixed. (See Fig. 8.) The numbering-wheels are also spur-wheels, the ones on shaft C being idle wheels. Each numbering-wheel on shaft F is fixed to a one-tooth Geneva wheel I, which gears to a twelve-notched and concaved Geneva wheel J, which is attached to each of the idle spur-wheels G³ on shaft C; but between all other numbering-wheels there are space-washers only. In 90 working the machine the paper is placed on the table A' to the usual adjustable gage and if in sheets sheet by sheet is fed in the usual manner adopted by paper-rollers to the stops K. As the machine revolves the cam K³ at the gap allows the roller K' to drop on the sheet, and the stop K rising the sheet 95 is delivered between the rollers B and numbering-wheels in D' D' for printing numbers. The cam K³ is adjustable as to its time of moving by the wheel C' to another position on its shaft C by a set-screw to permit 100 sheets to be fed variously to the machine two or more times, if the numbers require to be closer than is permitted by the free working of the numbering-wheels in one operation. The sheets then pass between B and B⁵ and 105 between B and B', these small rollers B⁵ and B' having cords to guide the sheets round B, and so to a delivery-box placed below B, but not shown.

The inking is operated by placing ink in 110 the ink-well N, which is adjustable, as shown, to the grooved roller M. M is driven by Geneva gear L on shaft C and a notched Geneva wheel L' on the spindle of M to move M a quarter-turn and give it a slight rest after 115

each movement. The four depressions in M are so arranged that the roller O shall not grind its face on M when M is at rest. The roller O' is the ink-spreading roller, moved slightly longitudinally by the arm and cam P, also secured to the wheel C', and any additional ink-rollers O³ O⁵ may be used.

On the left of Fig. 1 there is a sixteen-teeth wheel Q, fixed to the shaft of B; working a wheel Q' of forty-eight teeth through an adjustable idle wheel Q³, but so that the sixteen-teeth wheel Q may be changed for a twenty-four-teeth wheel. (Not shown.) Q', loose on the shaft C, has a cam Q⁵ attached to it, working the pin U when said pin is to be moved in and out of gear, so that when pin U projects sufficiently through the fixed disk T the star-wheel E⁰ contacts with it, and so operates the number-wheels in tenths or multiples of tenths, according to which set of change-wheels is operating the shaft F. This pin U is sometimes made to recede for a period sufficient to allow the disk D to make one or two revolutions without the star-wheel E⁰ contacting with it, thus allowing two or three sheets to be numbered alike by using the said sixteen-teeth wheel Q or the twenty-four-teeth wheel, (not shown,) respectively, for driving the said cam Q⁵. The fixed disk T, the center of which is coincident with the center of shaft C, has a number of tapped holes near its outer edge arranged in a circle for fitting in any pins for working the star-wheel E⁰, as explained, when the same is wanted to move more or less early to change the numbers at different points of the revolution, particularly for changing triplicate when using three numbering sets in a reel-frame. The change-gear E³, giving the three-teeth movement mentioned, would not number correctly when using three sets in a reel-frame for triplicate work, as the sixth contact of the star-wheel E⁰ on the pin U would show or print numbers "19, 10, 11" instead of "19, 20, 21." The insertion of three pins in the disk T for moving the shaft-wheel E⁰ after each impression obviates this error.

Sinking ciphers of usual construction are used to obviate printing ciphers before figures and letters or signatures may be placed before the figures, such as, "A3804," &c.

To take any numbering set out of gear for altering readings or to lay aside, the nicked nuts R, one at each spindle end of most numbering sets, are turned about a half-turn, so that the long slot in the head of each faces outward away from the gear to which the set is geared on shaft C, and said set can be lifted out through said slots. To replace, the set is dropped with its spindle ends one in each slot of R and when in gear the heads R are turned about a half-turn, which not only will tighten them, but prevent them coming out of gear. When the heads R R are loosened,

the dovetailed ends S S can slide in the circular dovetailed grooves to alter the relative position of the sets if needed, and the tightening of R R secures these positions also.

In Figs. 16 and 17 the method of working the pin U when same is to be receded at intervals is shown: When said pin does not need to be receded, either the wheel Q', carrying the cam, is stopped by the idle wheel Q³ being removed or a plain pin is screwed to any of the other holes shown, which are placed in a circle as close as can be conveniently drilled and tapped for the purpose of taking any of the fixed pins described for contacting with E⁰. There is only one pin U that is needed to be withdrawn, as shown, by a spring and pushed forward by a cam, as shown, of well-known construction. The disk T is a fixture bolted to the frame A. The gearing composed of two teeth and a gap bridging the engraved figures in the numbering-wheels and marked G³ serve a similar purpose to the wheels on shaft C in other figures, all but the units one being attached to a twelve-notched Geneva wheel J and this geared to a one-tooth wheel I in each case, said wheels I being secured to adjacent numbering-wheels on shaft F, and on all other sets the numbering-wheels are idle, with merely bosses or washers between. It will be seen that there are no springs, pawls, ratchets, or the like between the star-wheel E⁰ and any of the number-wheels, so that each number-wheel is always in gear with the said E⁰, and so no number-wheel can be purposely or inadvertently altered, as is usually the case. I have previously used spur-wheels attached to the units and tens number-wheels on the outer sides of same, but such limit of numbering is two figures. I have never heard of spur-wheels being placed between the numbering-wheels for indefinite numbering, thus placing all number-wheels in gear.

In this invention any suitable sizes or materials may be adopted.

Having thus described my invention, what I claim, and desire a patent of the United States of America, is—

1. In a numbering-machine, in combination, a shaft carrying a series of single-tooth Geneva wheels with spur-wheels attached thereto, these operating on a series of Geneva twelve-notched and concaved wheels attached to which are spur-wheels, this series operating on a series of spur-wheels, to each of which is attached a numbering-wheel with ten figures engraved thereon each, the whole substantially as described and shown and for the purposes set forth.

2. In a numbering-machine, in combination, single-tooth Geneva wheels attached to spur-wheels with twelve notched and concaved Geneva wheels attached to spur-wheels, these geared to spur-wheels that are attached to the number-wheels, the whole

4
being mounted in a reel-frame for operating substantially as shown and described and for the purposes set forth.

3. In a numbering - machine, Geneva
5 wheels, spur-wheels, engraved number-wheel
mounted in a reel-frame in combination with
a series of spur change-wheels, said gearing
mounted in a reel-frame and worked by a
star-wheel all substantially as set forth.
- 10 4. In a numbering - machine, Geneva
wheels, spur - wheels, engraved number-

wheels, reel-frames, change spur-wheel gearing and star-wheel, in combination with a movable pin for operating said star-wheel at intervals, all substantially as set forth.

Dated this 28th day of December, A. D. 15
1904.

CHARLES BOWTELL SMITH.
